US00D900370S

(12) **United States Design Patent** (10) **Patent No.:** **US D900,370 S**
(45) **Date of Patent:** **** Oct. 27, 2020**

(54) **COMBINED SALT LAMP AND OIL DIFFUSER**

(71) Applicant: **Bear Down Brands, LLC**, Huntington Beach, CA (US)

(72) Inventors: **ShiFei Meng**, Xiamen (CN); **Dayne Nathaniel Tanner**, Concord, CA (US)

(73) Assignee: **Bear Down Brands, LLC**, Huntington Beach, CA (US)

(**) Term: **15 Years**

(21) Appl. No.: **29/659,317**

(22) Filed: **Aug. 8, 2018**

(51) **LOC (12) Cl.** **26-05**

(52) **U.S. Cl.**

USPC **D26/51**

(58) **Field of Classification Search**

USPC D26/9, 51, 93, 135, 137; D11/131, D11/131.1, 143, 152-154, 184; D23/355, D23/356, 359, 360, 364, 366, 367; D7/509, 591, 598

(57) **CLAIM**

The ornamental design for a combined salt lamp and oil diffuser, as shown and described.

DESCRIPTION

FIG. 1 is a rear elevational view of our new design; FIG. 2 is a top plan view thereof;

FIG. 3 is a front elevational view thereof;

FIG. 4 is a bottom plan view thereof;

FIG. 5 is a left side view thereof;

FIG. 6 is a right side view thereof; and,

FIG. 7 is a front perspective view thereof.

The broken lines in the drawings depict portions of the combined salt lamp and oil diffuser that form no part of the claimed design.

1 Claim, 4 Drawing Sheets
